UNITED STATES PATENT OFFICE.

ARTHUR H. GIBSON, OF EASTON, PENNSYLVANIA, ASSIGNOR TO INGERSOLL-RAND COMPANY, OF NEW YORK, N. Y., A CORPORATION OF NEW JERSEY.

MINING-MACHINE.

1,082,318.

Specification of Letters Patent. Patented Dec. 23, 1913.

Application filed November 18, 1908. Serial No. 463,211.

To all whom it may concern:

Be it known that I, ARTHUR H. GIBSON, a subject of the King of Great Britain, and resident of Easton, in the county of Northampton and State of Pennsylvania, have invented a new and useful Improvement in Mining-Machines, of which the following is a specification.

My invention relates to improvements in mining machines and is directed to machines which are well adapted for use in operating upon coal.

My invention relates more particularly to improvements in coal cutting and loading machines and contemplates the provision of a truck on which is mounted a puncher, said truck also carrying a conveyor so arranged that it will convey the coal from the front of the machine to the rear of the same where it may be removed to any desired point.

My invention further contemplates certain improvements in the construction, form and arrangement of the several parts of a coal cutting and loading machine whereby the coal may be cut and loaded in a very simple and effective manner.

A practical embodiment of my invention is represented in the accompanying drawings in which,

Figure 1 represents the coal cutting and loading machine in side elevation; Fig. 2 is a top plan view of the same, Fig. 3 is an enlarged transverse vertical section taken in the plane of the line A—A of Fig. 1, looking in the direction of the arrows, Fig. 3^a is a detail side view of the puncher cylinder, Fig. 4 is a horizontal section taken in the plane of the line B—B of Fig. 3, looking in the direction of the arrows, Fig. 5 is a transverse vertical section taken in the plane of the line C—C of Fig. 1, looking in the direction of the arrows, Fig. 6 is a detail view showing the worm gear mechanism for swinging the puncher vertically, Fig. 7 is a section taken in the plane of the line D—D of Fig. 6, looking in the direction of the arrows, Fig. 8 is an enlarged detail longitudinal section through the lower portion of the machine, and Fig. 8^a is a continuation of the same.

The track for the coal cutting and loading machine is formed in short sections comprising the bottom plate 1 of sheet metal and the usual track rails 2, 2. These track

sections may be connected by tie plates 3 and bolts 4 engaging abutting ends of the track rails 2, for forming a continuous track.

The coal cutting and loading machine is adapted for movement along the track, the body or platform of the said machine being denoted by 5 and its front and rear trucks by 6 and 7, which trucks carry the usual traction wheels 8 and are pivotally connected to the body or platform 5.

The machine is preferably moved along the track by providing a winch 9 around which is wound a rope or cable 10, the ends of which rope or cable being provided with hooks 11 for engaging holes 12 in one of the track rails 2 at points to the front and rear of the winch, so that the machine is moved to the front and rear according to the direction in which the winch is turned. This winch is provided with a small gear 14 having a crank handle 15. The winch is prevented from turning in a reverse direction, as, for instance by providing pawls 16, 17, either one of which is fitted to engage the gear 14 according to whether the winch is to be held against movement in one or the opposite direction. A suitable brake 18 is arranged to grip and release the traction wheels 8 of the rear truck 7, the handle 19 of which brake is engaged by a rack 20 for holding the brake in any desired adjustment.

The coal puncher cylinder is denoted by 21 and the pick by 22. The pick is operated by pulsating columns of air through flexible tubes 23, 24, leading to the puncher cylinder 21 from the cylinder 25 of a pulsator, which pulsator is operated by a motor, such, for instance, as a motor 26, the shaft 27 of which electric motor is connected to the shaft 28 of the pulsator through gears 29, 30.

The coal puncher cylinder 21 is longitudinally adjusted with respect to its trunnions 31, 32, as follows: The opposite sides of the cylinder 21 are provided with longitudinal undercut grooves 33, 34, which receive the heads 35, 36, of bolts 37, 38. Each of the bolts 37 passes through one of a series of holes 39 in the trunnion 31, and its end is provided with a nut 40 for clamping the cylinder rigidly to the trunnion. Similarly each of the bolts 38 extends through one of a series of holes 41 in the trunnion 32 and its end is provided with a nut 42 for clamping

the cylinder 21 rigidly to the trunnion 32. By this arrangement the puncher may be adjusted longitudinally to a limited extent with respect to its trunnions.

5 The puncher may be swung vertically into any desired angular position by the following mechanism: A worm gear 43 of ring form is frictionally held between the trunnion 31 and an outer ring 44, in the present 10 instance, by providing a plurality of bolts 45 projecting from the trunnion 31 through the ring 44 and interposing springs 46 between the outer face of the ring 44 and the heads 47 of the said bolts. The trunnions 15 31 and the ring 44 with the frictionally clamped worm gear 43, are rotatably mounted in the side frame 48 of a support 49 and the trunnion 32 is rotatably mounted in the side frame 50 of said support. A ring 51 is 20 secured by screw-bolts 52 to the side frame 48 with its inner edge overlapping the ring 44, thus serving as a keeper for retaining the trunnions in their position in the side frames of the support. A worm 53 is slidably 25 mounted on a vertical shaft 54, which worm meshes with the worm gear 43. This worm is yieldingly held in its normal position on the said shaft by springs 55, 56, interposed between the said worm and upper and lower 30 ball thrust bearings 57, 58, respectively. The worm 53, shaft 54, springs 55, 56 and the ball thrust bearings 57, 58, are located in a recess 59 in the side frame 48. The shaft 54 is rotated by a hand wheel 60 through 35 intermeshing pinions 61, 62.

The coal puncher may be swung laterally into different desired angular positions by the following mechanism: A worm gear 63 of ring form is frictionally held between 40 the support 49 and a ring 64, in the present instance, by providing a plurality of bolts 65 projecting from the ring 64 through the base of the support 49 and interposing springs 66 between the base of the said support 49 and the heads 67 of the said bolts. A ring 68 is secured to the body or platform 5 by screw bolts 69, the inner edge of which ring overlaps the base of the support 49 for retaining the support in its position. A 50 worm 70 is slidably mounted on a horizontal shaft 71 and meshes with the worm gear 63. This worm is yieldingly held in its normal position by springs 72, 73, interposed between the worm and side ball thrust bearings 74, 75. The worm 70, shaft 71, springs 72, 73, and ball thrust bearings 74, 75, are housed within a recess 76 in the body 5 of the machine. This shaft 71 is rotated from a hand wheel 77 through a sprocket chain 60 78 and sprockets 79, 80.

The means which I have shown for conveying the coal from a point in front of the machine to a point to the rear thereof, is constructed, arranged and operated as fol-

lows: A conveyer belt 81 passes around a roll 65 82 located at the front of the machine and around one of a pair of feed rolls 83, 84, located at the rear of the machine. This conveyer belt extends from a point a distance in front of the forward truck 6 to a point a 70 distance to the rear of the rear truck 7, which belt passes under the forward truck 6 between the traction wheels 8 and then over the rear truck 7. The front conveyer belt roll 82 is mounted in the side of a conveyer 75 trough 85 adjacent to the front end of the said trough. The bottom 86 of this trough rests upon the bottom plate 1 of the track when the conveyer is in use. A sectional transverse partition plate 87 is interposed 80 between the upper and lower portions of the conveyer belt, which sectional partition plate extends practically the entire distance from the front roll 82 to the rear rolls 83, 84. The lower portion of the conveyer belt at the 85 rear end of the machine, runs along and is supported upon the floor section 88 of the body or platform 5 and the lower portion of the conveyer belt at the front end of the machine runs along and is supported upon the bottom 86 of the conveyer trough 85. This trough 85 may be raised a sufficient distance to permit it to clear the tops of the track rails when the machine is moved from place to place and is supported in such raised 90 position by any suitable means, such, for instance, as providing a bail 89 hinged to the conveyer trough and arranged to be engaged with a shoulder 90 at the front end of the body or platform 5, for supporting the front 100 end of the trough in its raised position and providing the sides of the body or platform 5 with holes 91 for receiving one or more suitable bars 92 indicated in dotted lines in Fig. 8*, which may be inserted beneath the 105 sectional partition 87 at the rear end of the conveyer trough. The feed rolls 83, 84, are geared together by gears 93, 94, and grip the conveyer belt 81 between the same so as to prevent the conveyer belt from slipping 110 in case it becomes slippery.

The conveyer belt is driven from the motor 26 as follows: The shaft 28 of the pulsator is provided with a bevel gear driving connection 95, 96, with one member 97 115 of a friction clutch of any well known or approved form, mounted on a cross shaft 98, the other clutch member 99 of which is fixed to rotate with the said shaft 98. A hand lever 100 is employed for clutching 120 the member 97 to and releasing it from the member 99, whereby the rotation of the shaft 98 is controlled. This shaft 98 is provided with a sprocket wheel 101 which is connected to a sprocket wheel 102 on the shaft of 125 the roll 84, by a chain 103. This friction clutch forms a slip connection between the motor and endless conveyer so that if the

conveyer should become clogged or unintentionally stopped in its movement, the slipping of the clutch connection between it and the motor would absolutely prevent any 5 breakage of the parts.

The front truck 6 is pivoted to the body or platform 5 of the machine as follows: A bolt 106 projects upwardly from the truck 6 through the bottom of the body or platform 5 concentric with the worm gear wheel 63. A nut 107 has a screw-threaded engagement with the upper end of the bolt 106 and a block 108 is interposed between the nut 107 and the bottom of the body or platform 5. After the machine has been moved to the desired point, the nut 107 may be tightened for rigidly mounting the front end of the body or platform 5 on the truck 6. The rear truck 7 is pivotally connected to the body or platform 5 of the machine by providing the truck with an uprising stud 109 which enters a lug 110 depending from the floor section 88 of the body or platform 5.

The operation of the machine is as follows: The machine is moved along the track into proximity to its work. One end of the rope or cable 10 is then attached to the track rail at a distance in front of the winch 9 and the other end of the said rope or cable is attached to the track at a distance from the rear of the said winch. The operation of the winch will then permit the machine to be moved to a limited extent toward and away from the work as may be desired. The 25 conveyer trough may then be released from its raised position and the trough dropped down on to the track between the track rails 2, 2. The puncher may then be swung laterally and vertically either for the purpose of undercutting or for breaking down the face of the coal as may be desired. These laterally and vertically swinging movements of the puncher may be accomplished by manipulation of the hand wheels 77 and 60. The 30 coal may now be shoveled on to the flat belt conveyer at the front of the machine. The conveyer belt may then be moved by connecting its driving means with the motor for conveying the coal from the point at the front of the machine to the point at the rear of the machine where the said coal may be deposited into any desired receptacle, as for instance, into the buckets 104 of an endless conveyer 105 driven from any suitable source 35 of supply, and this conveyer may deposit the coal into a regular mine car or wagon. When the machine has cut the coal as far as possible and the front wheels have reached nearly the end of the track, another short section of track is laid in front of the preceding section and is secured thereto by tie plates 3 and bolts 4. It will be seen that as the machine is moved forward or backward by the winch, the trough of the belt

conveyer slides along on the bottom plate 1 of the track section.

A yielding worm connection between the puncher cylinder trunnions and their support and between the support and the body or platform of the machine, absolutely prevents the breakage of the parts when the puncher strikes a glancing blow on the face of the coal, the said yielding connection permitting a slight rotary yield of the puncher in both a lateral and a vertical direction according to the direction of the glancing movement of the puncher. The worms will be automatically returned to their adjusted position by the springs engaging the worms as hereinabove set forth. The frictional clamping of the worm gears will permit the gears to slip before they will break under any undue twisting strain thereon and will also serve to prevent any undue wear on the teeth of the gears owing to the slight working around of the gears, thus presenting new teeth to the action of the worms. This frictional clamping of the worm gears may be adjusted to any desired degree of resistance. If the puncher is thrown out of its adjusted position to any considerable extent, the slipping of the gears will permit the puncher to remain in such position and still operate, thus absolutely preventing the breakage of any 95 of the parts. A still further valuable point in this machine is the lateral adjustment of the puncher without the necessity of affecting the adjustment of its trunnions. The ball thrust bearings for the worm centering 100 springs serve to materially lessen the effort required to rotate the worms by the operator of the machine.

By locating the conveyer as set forth, it will be seen that it is not in the way of the 105 machine when it is working; that it may be readily transported from place to place with the machine, and that the very desirable feature of a ready removal of the coal from the front end to the rear of the machine is 110 provided for in a very simple and effective manner.

What I claim is:

1. A mining machine including a portable platform, a puncher mounted thereon, and yielding means for swinging the puncher laterally.
2. A mining machine including a portable platform, a puncher mounted thereon, and friction held means for swinging the 120 puncher laterally.
3. A mining machine including a portable platform, a puncher mounted thereon, yielding means for swinging the puncher laterally and yielding means for swinging 125 the puncher vertically.
4. A mining machine including a portable platform, a puncher mounted thereon,

- friction held means for swinging the puncher laterally and friction held means for swinging the puncher vertically.
5. A mining machine including a portable platform, a puncher mounted thereon, means for adjusting the puncher longitudinally, and yielding means for swinging the puncher laterally. 70
6. A mining machine including a portable platform, a puncher mounted thereon, means for adjusting the puncher longitudinally and friction held means for swinging the puncher laterally. 75
7. A mining machine including a portable platform, a puncher mounted thereon, means for adjusting the puncher longitudinally and yielding means for swinging the puncher vertically. 80
8. A mining machine including a portable platform, a puncher mounted thereon, means for adjusting the puncher longitudinally, and friction held means for swinging the puncher vertically. 85
9. A mining machine including a portable platform, a puncher mounted thereon, means for adjusting the puncher longitudinally, yielding means for swinging the puncher laterally and yielding means for swinging the puncher vertically. 90
- 30 10. A mining machine including a portable platform, a puncher mounted thereon, means for adjusting the puncher longitudinally, friction held means for swinging the puncher laterally and friction held means for swinging the puncher vertically. 95
11. A mining machine including a portable platform, a support mounted thereon, yielding means for swinging the support horizontally and a puncher mounted on said support. 100
12. A mining machine including a portable platform, a support mounted thereon, friction held means for swinging the support horizontally and a puncher mounted on said support. 105
13. A mining machine including a portable platform, a support mounted thereon, yielding means for swinging the support horizontally, a puncher mounted on said support and means for swinging the puncher vertically. 110
- 50 14. A mining machine including a portable platform, a support mounted thereon, friction held means for swinging the support horizontally, a puncher mounted on said support and means for swinging the puncher vertically. 115
15. A mining machine including a portable platform, a support mounted thereon, yielding means for swinging the support horizontally, a puncher mounted on said support and yielding means for swinging the puncher vertically. 120
- 60 16. A mining machine including a portable platform, a support mounted thereon, 125
- friction held means for swinging the support horizontally, a puncher mounted on said support and friction held means for swinging the puncher vertically.
17. In a mining machine, a support, a puncher having its trunnions rotatably mounted in said support, a worm gear frictionally secured to one of the trunnions and means including a worm meshing with said gear, for swinging the puncher vertically. 70
18. In a mining machine, a support, a puncher having its trunnions rotatably mounted in said support, a worm gear frictionally secured to one of the trunnions, and means including a yielding worm meshing with said gear, for swinging the puncher vertically. 75
19. In a mining machine, a rotary support, a puncher mounted thereon, a worm gear frictionally secured to said support, and means including a worm meshing with said gear, for swinging the support horizontally. 80
20. In a mining machine, a rotary support, a puncher mounted thereon, a worm gear frictionally secured to said support, and means including a yielding worm meshing with said gear for swinging the support horizontally. 85
21. In a mining machine, a rotary support, a puncher having its trunnions rotatably mounted in said support, a worm gear frictionally secured to one of said trunnions, and means including a worm meshing with said gear, for swinging the puncher vertically. 90
22. In a mining machine, a rotary support, a puncher having its trunnions rotatably mounted in said support, a worm gear frictionally secured to one of said trunnions, and means including a yielding worm meshing with said gear, for swinging the puncher vertically. 95
23. In a mining machine, a rotary support, a puncher pivoted to swing vertically thereon, a worm gear frictionally secured to said support, and means including a worm meshing with said gear, for swinging the support horizontally. 100
24. In a mining machine, a rotary support, a puncher pivoted to swing vertically thereon, a worm gear frictionally secured to said support, and means including a yielding worm meshing with said gear, for swinging the support horizontally. 105
25. In a mining machine, a rotary support, a puncher having its trunnions rotatably mounted therein, a worm gear frictionally secured to one of said trunnions, means including a worm meshing with said gear, for swinging the puncher vertically, a worm gear frictionally secured to said support, and means including a worm meshing with said gear for swinging the support horizontally. 110

26. A mining machine including a puncher, a pulsator for operating the puncher, a motor for driving the pulsator, and yielding means for swinging the puncher horizontally.
27. A mining machine including a puncher, a pulsator for operating the puncher, a motor for driving the pulsator and friction held means for swinging the puncher horizontally.
28. A mining machine including a puncher, a pulsator for operating the puncher, a motor for driving the pulsator, yielding means for swinging the puncher horizontally and yielding means for swinging the puncher vertically.
29. A mining machine including a puncher, a pulsator for operating the puncher, a motor for driving the pulsator, friction held means for swinging the puncher horizontally and friction held means for swinging the puncher vertically.
30. A mining machine including a puncher, yielding means for swinging the puncher laterally, yielding means for swing-
- ing the puncher vertically, means for positively moving the machine toward and away from its work and holding it in any adjusted position and a conveyer arranged to transport the material from a point at the front of the machine to a point at the back of the machine.
31. A mining machine including a puncher, friction held means for swinging the puncher laterally, friction held means for swinging the puncher vertically, means for positively moving the machine toward and away from its work and holding it in any adjusted position and a conveyer arranged to transport the material from a point at the front of the machine to a point at the back of the machine.

In testimony, that I claim the foregoing as my invention, I have signed my name in presence of two witnesses, this seventeenth day of November 1908.

ARTHUR H. GIBSON.
